UNITED STATES PATENT OFFICE.

JOSEPH WEATHERBY, JR., AND ANDREW J. DULL, OF HARRISBURG, PENNSYLVANIA;
SAID WEATHERBY ASSIGNOR TO SAID DULL.

MAGNETIC SEPARATOR.

1,024,045.

Specification of Letters Patent.

Patented Apr. 23, 1912.

Application filed December 21, 1908. Serial No. 468,645.

To all whom it may concern:

Be it known that we, JOSEPH WEATHERBY, Jr., and ANDREW J. DULL, of Harrisburg, Dauphin county, Pennsylvania, have invented certain new and useful Improvements in Magnetic Separators; and we do hereby declare the following to be a full, clear, and exact description of the same, reference being had to the accompanying drawings, forming a part of this specification, and to the figures and letters of reference marked thereon.

This invention relates to the separation or classification of materials, particularly minerals, having different magnetic susceptibility or permeability, the object of the invention being to improve the art and apparatus by utilizing the forces of magnetism and momentum or centrifugal force acting in the same direction as active agents in effecting the separation of the more permeable or susceptible materials from the less permeable or susceptible materials.

The invention contemplates the introduction of the comminuted materials into a magnetic field of sufficient density to produce a tendency in the materials to separate, thereby producing a greater or less movement of the more permeable or susceptible material in the direction of convergence of the lines of magnetic force and in immediately augmenting such movement of the said more susceptible material by the combined action of the magnetic field and centrifugal force, and in supplementing such action by the force of gravity in aiding the movement of the more susceptible material toward the discharge point.

The invention further contemplates the separation of materials of the character specified by subjecting them to the action of a field of sustained magnetic intensity, but of progressively increasing area from the entrance toward the discharge point, whereby the bodies of materials become more and more attenuated and liability of mechanical interference of each with the other tending to prevent separation is progressively reduced.

In the practical embodiment of the apparatus for carrying the present invention into practice, the air gap forming the magnetic field is preferably produced between conical terminals, one within the other, and of opposite sign, the entrance being formed at the

apex and the discharge at the base of the conical magnetic field thus produced.

While the embodiment of the invention illustrated in the accompanying drawings, and to be hereinafter specifically described, is a preferred embodiment, it will be understood that mechanism for carrying the present invention into practice is susceptible of many modifications which will at once suggest themselves to those skilled in the art, and hence it is not desired to limit the invention to any particular mechanism.

Referring to the accompanying drawings: Figure 1 is a transverse section in a vertical plane through the apparatus wherewith the present invention may be carried into practice. Fig. 2 is a detail section of a portion of the outer terminal of the magnetic circuit and illustrating the spiral for giving a line distribution of the magnetic lines of force.

In the form of apparatus illustrated, the terminals of the magnetic circuit between which the magnetic separating field is formed are each of conical formation, thus the inner terminal A takes the form of a cone which may be conveniently mounted on or constitute one pole piece of an electromagnet core B, magnetism being induced in the core and pole piece by a suitable coil C of approved design. The other terminal D is formed with an internal conical surface, thus taking the form of a hollow cone D, the base of which may be conveniently connected by standards E with a base F, preferably of magnetic material and adapted to complete the magnetic circuit from the lower end of the core B. The supports E may, under some circumstances, constitute magnetic cores, and as illustrative of this a coil is indicated in dotted lines at G in Fig. 1, although it will be understood that the particular arrangement for exciting or producing the magnetic circuit with conical internal and external terminals of opposite sign is not of paramount importance, and may be varied to suit particular conditions, or the ideas of particular designers. Both terminals are conveniently stationary in operation, although in order to provide a convenient and efficient means for adjusting the width of the magnetic field one of said terminals is preferably made adjustable with relation to the other, thus, as shown, the terminal A, together with the core B, may be adjusted vertically by the screw H adapted

ed to be operated by gearing, and a hand wheel h .

Located within the air gap or magnetic field is a rotary cone K of relatively thin 5 non-magnetic material, or of material having a very low susceptibility or permeability, this cone K being conveniently journaled on the non-adjustable terminal, as, for instance, by ball bearings k . At its upper end it is in 10 communication with or forms the entrance opening for the materials to be separated. As a preferred construction, the cone K is at the upper end, flared outwardly to form an enlargement K' provided with a horizontal 15 diaphragm k' having apertures near its periphery. The material to be separated is fed down from a hopper L to the center of the diaphragm k' , being thence distributed by centrifugal action toward the periphery of the diaphragm, where it will drop 20 by gravity through the apertures and thence pass down into the magnetic field. In order to prevent entry of large pieces which might injure the separator, a flaring or dish-shaped 25 screen M may be introduced in the upper end of the entrance aperture for the cone and adapted to rotate therewith, whereby the large or heavy particles not passing through the screen will be discharged over the edge 30 of the same. The feed from the hopper L may be regulated by a vertically adjustable sleeve L' and power for rotating the non-magnetic cone may be applied through a pulley N on the upper end of the said cone 35 and a belt or other preferred form of gearing such as indicated at N' .

Susceptible or permeable material passing down through the magnetic field will naturally be attracted to a greater or less degree 40 toward that terminal of the magnetic circuit upon which the magnetic lines of force converge, and inasmuch as in the present invention it is proposed to take advantage of momentum or centrifugal force to assist in 45 the complete separation of the materials, provision is made for causing the lines of magnetic force to converge toward the outer terminal, the means adapted preferably being to subdivide the inner face of the outer 50 terminal into a succession of ridges giving a line distribution at that side of the magnetic field. Furthermore, inasmuch as it is designed that with the present invention the magnetic force shall itself assist and be 55 assisted both by centrifugal force and by gravity in feeding the material toward the discharge point, the said inner surface of the outer terminal is preferably arranged in the form of a spirol projection or rib d . The 60 accompanying illustration shows a single spiral, but it is obvious that two or more spirals may be employed where the pitch is to be increased, thus permitting of relatively fine gradations or distances between adjacent crests in a vertical line. With this ar-

angement the rotary non-magnetic cone is preferably located in proximity to the face of the outer terminal, leaving the major portion of the free air gap between the rotary cone and the inner terminal.

At the larger or discharge end of the cone the air gap is divided by an annular partition O on one side of which the more susceptible or permeable material is adapted to be discharged while the unaffected or less permeable material is discharged on the opposite or inner side of the said partition, the partition O thus forming in effect separate hoppers in the bottom of which discharge openings σ may be located.

In operation, the comminuted material fed from the hopper into the entrance end of the rotary cone drops down into the magnetic field between the terminals of the magnetic circuit, and owing to the increasing surface area toward the discharge end, the said material at once begins to attenuate, and while the full capacity of the entrance end may be fed to the separator the material at the discharge end is so distributed that every possible particle of permeable or susceptible material is effectually relieved from its entanglement with less permeable or susceptible material, and is free to move under the influence of the lines of magnetic force toward the rotary cone.

In its travel through the magnetic field, the material is subjected to the action of a great number of successive converging fields of magnetic force and is being constantly rolled and agitated in its passage over the inner conical surface. Material which has yielded to the influence of the magnetic lines of force and moved toward or against the inner face of the rotary cone at once feels the influence of centrifugal force which tends first to hold the material against said surface, and secondly by reason of the divergent walls to cause said material to feed toward the larger end of the cone. The direction of the spiral on the inner face of the outer terminal with relation to the direction of rotation of the cone is such that material held against the inner face of the rotary cone is constantly drawn more tightly against said face and the line of attraction with respect to any particular point on the cone moves constantly downward or toward the discharge end, thus the magnetic pressure also tends to move the susceptible material toward the discharge end, and in this respect acts in concert with both centrifugal force and gravity.

It will be noted that the material passing through the separator is subjected for a prolonged period to the action of a sustained magnetic field, that is to say, the magnetic field does not, as heretofore, rapidly decrease in intensity after a point of major separation has been passed, but the magnetic

field as a whole extends with practically a uniform intensity throughout the major portion of the distance from the top to the bottom of the cones, although it will be understood that owing to special designing and the tendency of the magnetic lines of force to follow the paths of least resistance, the intensity of the field may vary somewhat at different points, yet this is of small moment.

The inclination of the faces of the conical members with respect to the horizon is greater than the angle of repose of the material passing through under the influence of gravity, with the result that a fixed inner member may be employed over which the material will flow freely by gravity alone. As a further result of the inclination of the inner face of the rotary member, material once contacting therewith will be held by centrifugal force if aided by even a weak magnetic attraction and in its progress toward the discharge point under the influence of centrifugal force magnetic attraction and gravity it will travel over the surface of the rotary member in a spiral path, the length of which is many times the direct distance from the entrance to the discharge, whereby the non-susceptible material is effectually shaken out or disengaged from the susceptible material.

Having thus described the invention, what we claim as new and desire to secure by Letters-Patent, is:

1. In a magnetic separator, the combination with a conical magnetic pole piece having its exterior conical face inclined to the vertical at an angle greater than the angle of repose of the material to be separated, whereby the material will flow down over said surface by gravity alone, of a conical rotary member of non-magnetic material surrounding said pole piece and uniformly spaced therefrom to form a conical passageway for the material to be separated, and a fixed conical pole piece surrounding and in proximity to the rotary member, the construction being such that the lines of magnetic force converge toward the outer fixed pole piece.

2. In a magnetic separator, the combination with a conical magnetic pole piece hav-

ing an exterior conical face inclined at an angle greater than the angle of repose of the material to be separated, whereby the material will flow down over said surface by gravity alone, of a conical rotary member of non-magnetic material surrounding said pole piece and spaced therefrom to form a conical passageway for the material to be separated, a fixed conical magnetic pole piece surrounding and in proximity to the rotary member and having its inner face serrated whereby the lines of magnetic force are caused to converge outwardly and an annular partition interposed between the base of the inner conical pole piece and inner face of the rotary member, whereby the material passing downwardly in proximity to said faces will be separated in accordance with the magnetic susceptibility of the material.

3. In a magnetic separator, the combination with a fixed conical magnetic pole piece having its exterior conical face inclined at an angle greater than the angle of repose of the material to be separated, whereby the material will flow down over said face by gravity alone, of a conical rotary member of non-magnetic material surrounding said pole piece and spaced therefrom to form a conical passageway for the material to be separated, a fixed conical pole piece surrounding and in proximity to the rotary member and having its inner face spirally serrated from top to bottom, whereby the lines of magnetic force converge toward the rotary member, and an annular partition interposed between the lower ends of the inner conical pole piece and rotary member, whereby the material is separated into annular zones in accordance with its magnetic susceptibility, and the material of less susceptibility will be advanced by gravity and substantially free from mechanical agitation while the more susceptible material will be advanced by magnetic action, centrifugal force and gravity combined.
